TAMPERPROOF HOOK AND EYE

Nathan Rodney Schwartz, Brooklyn, N. Y., as
signor to Saran Research Corporation

Application June 23, 1943, Serial No. 492,170

1 Claim. (Cl. 292—106)

1

This invention refers to hook and eye closures and more particularly to means for preventing the unauthorized disengagement of a hook from an eye.

Hook and eye closing means are frequently employed to close screen doors, shower room doors, locker room doors, lavatory doors, window screens and similar entrances from within. It has been found however that these locking means are not at all secure, since a recess remains between the member to which the hook is secured and the member to which the eye is secured. It is relatively simple for a person seeking unauthorized entrance to a premises so locked, to place a knife or other sharp instrument into the recess below the hook, and by moving the knife or other instrument upward, to disengage the hook from the eye.

With this in view, it is the main purpose of the present invention to provide a conventional hook of this character with slidable locking means to prevent its disengagement from its eye, when such disengagement is not desired.

A further feature of the present invention is to provide a slidable latch for a hook, which, when in operative position, will prevent its disengagement from its eye.

Another aim of the present invention resides in the provision of a slidable sleeve for a hook, the sleeve having an integrally formed finger grip for easy manipulation.

And still another advantage of the present invention lies in the provision of a tamper-proof attachment for a hook, made from a unitary piece of material.

And yet another aim of this invention resides in the provision of a tamper-proof attachment for a hook, which is inexpensive to manufacture, yet highly efficient in operation.

These and other meritorious objects and advantages, which will become more fully apparent as the description hereof proceeds, are accomplished by the novel construction, combination and arrangement of few and simple parts, hereinafter described and illustrated in the accompanying drawing, forming a material component of this disclosure, and in which:

Figure 1 is a front elevational view of a conventional hook and eye, provided with the tamper-proof attachment of the present invention, the device being shown in locked position.

Figure 2 is a sectional view, the section being taken on Figure 1, lines 2—2 thereof.

Figure 3 is a perspective view of a hook, provided with the tamper-proof attachment of the

2

present invention, the attachment being shown in inoperative or unlocked position.

Figure 4 is a cross-sectional view of the device, the section being taken on line 4—4 of Figure 3.

Referring in greater detail to the drawing, numeral 10 designates in general the shank of a hook, one end of which is turned upon itself, as at 11, to form a circular retaining member for a screw eye 13 the circular head of which is retained in circular member 11, its screw end 12 being free to be imbedded into a support 14, such as a door.

The other end of shank 10, is curved upwardly as at 15 and then downwardly as at 16 to form a point or bill.

To form a locking means, there is provided an eye having a circular head 17 terminating at its other end in a screw 18 which may be imbedded in a mating support 19 such as a door frame. 20 These elements are conventional and in themselves form no part of the present invention.

The latch of the present invention is made from a unitary piece of material, such as metal or other suitable material. The material used is a narrow, 25 rectangular piece its width being such that, when it is bent to form a sleeve, the diameter thereof will be very slightly in excess of the diameter of the shank of a conventional hook. Sleeve member 20 is so applied upon shank 10, that the lateral 30 edges of said sleeve member meet at the underside of said shank 10.

At the center of the latch, a tongue is formed by providing slits in the material, which extend from the outer edge rearwardly to substantially 35 midway the length of said latch. This tongue, when the latch is applied upon a hook, is turned upwardly to form a finger-grip 24 as is illustrated in the drawing.

The device is assembled by turning the rear 40 portion of the material from which the latch is made, from the rear end to the point where the slits in the material begin, about shank 10. The front portion of the material, from the front edge to the end of the slits will thus form two parallel 45 fork members 21 and 22, the said fork members being created by the provision of said finger-grip 24. This too is clearly illustrated in the drawing. The length of sleeve member 20 including the forked parallel members 21 and 22 is equal 50 to the length of the shank of a hook from its upturned front 15 to the beginning of the rounded end portion 11 of shank 10.

In its application, rounded sleeve member 20 will embrace shank 10 at substantially its rear 55 half. Finger grip 24 will be positioned upon the

upper surface of shank 10, and forked members 21 and 22 will be positioned at the front half of shank 10 when the device is in an inoperative position.

In operation, after bill 16 has been engaged in eye 17, sleeve member 20 is manually moved forward upon shank 10 by manipulating finger-grip 24 in a conventional manner. Forward movement of the sleeve member 20 upon shank 10 will be checked at the point of contact between finger grip 24 and upturn 15 at the front of shank 10. As is illustrated in Figure 1, fork members 21 and 22 will lie immediately below eye 17 making it impossible to withdraw bill 16 from eye 17 until the sleeve member is moved back upon shank 10 to assume the position illustrated in Figure 3, whereupon disengagement is possible.

Thus it will be seen that there has here been disclosed a very simple yet highly efficient tamper-proof attachment for a conventional hook and eye in the preferred embodiment. It is to be understood however that this disclosure is to be regarded as illustrative and descriptive and not as limitative or restrictive to the exact details shown, applicant reserving the right to make such minor changes in the construction of this device as may come within the scope of the appended claim without thereby departing from the spirit of the present invention.

Having thus described the invention, what is 30

claimed as new and desired to secure by Letters Patent, is:

A latch for a hook adapted to engage an eye, said hook comprising a shank formed into a loop at its rear and into a bill at its front, a sleeve member slidably mounted on said shank, said sleeve member partially divided into three longitudinal sections, said sections extending rearwardly on said sleeve member from the outer edge thereof to substantially half the length of said sleeve member, the outer two of said sections adapted to engage said bill when the latch is in locked position, and the section between said slits forming a tongue turned upwardly to constitute a finger grip.
